HORN MOTOR AND RELAY UNIT

William J. Rady, Anderson, Ind., assignor to General Motors Corporation, Detroit, Mich., a corporation of Delaware

Application March 11, 1940, Serial No. 323,245

5 Claims.

(Cl. 177—7)

This invention relates to electric horns particularly for automobile use. An automobile horn is generally operated by a push button at the top of the steering column and in the center of the steering wheel. In order that the current carried by the horn button be reduced to the minimum, the horn button is not directly connected to the electric horn or to the storage battery but indirectly thereto through a relay. Heretofore the horn relay was a unit separate from the horn itself. It is an object of the present invention to combine the horn relay with the horn motor.

Further objects and advantages of the present invention will be apparent from the following description, reference being had to the accompanying drawing wherein a preferred embodiment of the invention is clearly shown.

In the drawing:

Fig. 1 is a plan view of a motor and relay unit for an electric horn.

Fig. 2 is a sectional view on line 2—2 of Fig. 1.

Fig. 3 is a view in the direction of the arrow 3 of Fig. 1.

Fig. 4 is a sectional view on the line 4—4 of Fig. 3.

Fig. 5 is a wiring diagram.

Referring to the drawing, the horn comprises a collar 20 having a central opening or throat 21 leading into a projector 22, a fragment of which is shown. The collar 20 cooperates with the diaphragm 23 to form an air compression chamber from which the sound vibrations start when the diaphragm is oscillated. Screws 25 and nuts 26 secure to the collar 20 a gasket 27, the diaphragm 23 and the base frame 31 of a motor 30.

Motor 30 comprises an E-shaped magnet core 32 comprising a plurality of laminations connected to each other by rivets 33 with brackets 34 which are attached to the frame 31 by studs 35 and nuts 36. The core 32 is centrally apertured to receive a rod 40 of hexagonal cross-section having a threaded end receiving a nut 41 which, when tightened, clamps to the rod 40 the diaphragm 23 located between two clamping washers 42 and 43. Nuts 45 and 45a threaded on rod 40 secure armature 46 and armature leaf spring 47 to the rod 40. The rod 40 carries a nut 50 for controlling the horn circuit breaker which comprises a stationary contact 51 mounted on a relatively rigid bracket 52 and a movable contact 53 mounted on a leaf spring plate 54 and movable within a hole in an insulating plate 55 with which the nut 50 directly engages.

Referring to Fig. 3, the parts 52, 55 and 54 form a part of a stack of flat laminations, which stack includes also a terminal plate 56, insulation plate 57, terminal plate 58, a contact bracket 59, insulating washer 60 and armature leaf spring

47, all of which are supported by a U-shaped pedestal 61. These parts are secured to the pedestal by a plurality of rivets 62 which are insulated from all the parts of the stack except 5 the uppermost part, namely the contact bracket 52. The rivets 62 therefore provide an electrical connection between the bracket 52 and the pedestal 61 which is grounded through the horn motor frame 31, thus providing a ground connection for the contact 51 of the horn circuit breaker. As stated before, the contact 53 is mounted upon the leaf spring metal member 54 which engages a terminal plate 56. This plate 56 is connected, as shown in Fig. 1, by lead 64 10 with a horn motor magnet coil 65 located within the magnet core 32, and by a lead 66 with a resistance element 67 which is grounded. The function of the resistance 67 is to reduce sparking at the contacts 51 and 53. The other end 15 of the magnet coil 65 is connected by a lead 68 with an apertured ear 58a of bracket 58 which, being in electrical contact with contact bracket 59, has an electric connection with the contact 69 of the horn relay, which will now be described. Wire 89 leads from bracket 58 to other horns such as represented by horn magnet coil 65', lead 66' and circuit breaker contacts 53' and 51' in Fig. 5. Thus the relay of the disclosed horn will control also the circuit of other horns.

Relay contact 69 engages a movable contact 70 mounted on an armature 71 connected by a spring hinge plate 72 with a flange 73 of a Z-shaped bracket 74 (Fig. 4). Bracket 74 supports a central core 75 for a relay magnet coil 76. The head 77 of the core 75 acts as a pole face. One end of coil 76 is attached to core 75 and the other end is connected by wire 78 with an insulated terminal 79 to be connected with a horn button 90 (Fig. 5). The terminal 81, insulated from terminal 79 is to be connected with a battery 80 (Fig. 5). The terminal plate 83 and the Z-frame 74 are secured to the leg 61a of pedestal 61 by screws 84. The screws 84 provide an electrical connection between the terminal 40 plate 83 and the bracket 74, thereby connecting battery terminal 81 with contact 70 through the following connections: wire 82, terminal plate 83, screws 84, bracket 74, hinge 72, armature 71 and contact 70. The screws 84, the plate 83 and the bracket 74 are insulated from the leg 61a by insulating plates 85 and 86 and insulating bushings 87. The contacts 69 and 70 are normally open, the armature 71 being biased away from the core head 77 by spring hinge 72, said movement being limited by a stop 88 which engages the armature 71.

Referring to Fig. 5, the circuit of relay coil 76 is battery 80, terminal 81, wire 82, plate 83, Z-frame 74, core 75, coil 76, wire 78, terminal 79, 50 and horn button switch 90. When the switch

90 is closed, current will flow from the battery 80 to the horn relay and return through ground. The horn relay winding 76 being energized, the armature 71 will move toward the core head 77 to cause contact 78 to engage contact 69 thereby connecting the battery 80 with the horn magnet coil 65 through the following circuit: battery 80, terminal 81, wire 82, plate 83, screws 84, bracket 74, hinge 72, armature 71, contact 78, contact 69, contact bracket 59, terminal bracket 58, wire 68, coil 65, lead 64, connector plate 56, spring blade 54, contact 53, contact 51, contact bracket 52, rivet 62, pedestal 61 and horn motor base 31 connected with ground. The horn magnet 65 being energized, the armature 46 will move toward the pole faces of the core 42 in order to move the diaphragm 23 toward the right as viewed in Fig. 2. During this movement the nut 50 will engage the insulated strip 55 which in turn engages the contact blade 54 carrying the contact 53 which will be separated from the contact 51 in order to temporarily break the circuit of the magnet coil 65. The magnetic flux of the horn motor dies away during the further motion of the diaphragm 23 toward the right. Finally movement of the diaphragm reverses and it moves toward the left somewhat beyond its normal position and sufficient to cause the contacts 51 and 53 to close again, whereupon the cycle of operation is repeated as long as the horn button switch 90 remains closed.

From the foregoing description of the construction and mode of operation of the combined horn motor and horn relay unit it is apparent that I have provided a simple and economical construction whereby the horn relay is combined with the horn motor at small additional cost, thereby eliminating the relay as a separate unit to be separately manufactured and mounted upon the automobile.

While the embodiment of the present invention as herein disclosed constitutes a preferred form, it is to be understood that other forms might be adopted, all coming within the scope of the claims which follow.

What is claimed is as follows:

1. A horn structure including a base, a diaphragm supported on the base, an armature for operating the diaphragm, and an electromagnet for the armature mounted on the base, an U-shaped support having the open end directed toward the base, the support and the base including means for supporting the former on the latter, a stack including interrupter means operated by the armature and a stationary contact for a relay, the closed end of the U and the stack including means for supporting the latter on the former, a relay including a core, coil, frame, and moving member bearing a contact, said movable member cooperating with the stationary contact, the core and coil being contained within the U, and the horn structure including means for supporting the relay on the base.

2. A horn structure including a base, a diaphragm supported on the base, an armature for operating the diaphragm, and an electromagnet for the armature mounted on the base, a circuit breaker having a movable member actuated by movement of the armature, a U-shaped pedestal having the open end directed toward and mounted upon the base and supporting the circuit

breaker, said pedestal providing a stationary contact in addition to the circuit breaker, a relay contained with the U and including a core, coil, frame, and moving member bearing a contact, said movable member cooperating with the stationary contact, for controlling the circuit of the horn electromagnet, and means securing the relay core upon the pedestal.

3. A horn structure including a base, a diaphragm supported on the base, an armature for operating the diaphragm, and an electromagnet for the armature mounted on the base, a circuit breaker having a movable member actuated by movement of the armature, a U-shaped pedestal having the open end directed toward and mounted upon the base and supporting the circuit breaker, said pedestal providing a stationary contact in addition to the circuit breaker, a relay contained within the U and including a core, coil, frame, and moving member bearing a contact, said movable member cooperating with the stationary contact, for controlling the circuit of the horn electromagnet, insulating means carried by one leg of the pedestal for supporting the relay frame and core between the legs of the pedestal.

4. A horn structure including a base, a diaphragm supported on the base, an armature for operating the diaphragm, and an electromagnet for the armature mounted on the base, an U-shaped support having the open end directed toward the base, means for securing the support upon the base, a stack including interrupter means operated by the armature and a stationary contact for a relay, the closed end of the U and the stack including means for supporting the stack upon the support, a second stack including a terminal plate, a relay frame and insulators, one leg of said U-support and the said second stack including means for supporting the second stack upon the support, a relay including a core, coil, frame, and moving member bearing a contact, said movable member cooperating with the stationary contact, the relay core and coil being contained between the legs of the U and supported by the frame thereof from the second said stack, the horn structure including means for supporting the relay on the base.

5. In an electrically operated vibratory motor in which a movable part actuates a circuit breaker for periodically energizing and deenergizing the motor, the combination of a pedestal comprising a flat headed arch for rigidly supporting the circuit breaker from its head, a relay adapted to connect the motor and circuit breaker with a current source, means for supporting the relay coil and core between the side members of the arch, including a bracket, means rigidly connecting the bracket to a side member of the arch and electrically insulating the core from the pedestal, said bracket providing a flange extending across said one arch member, the armature of said relay being hinged to said flange and extending across the arch and beyond the second side member of the pedestal, said circuit breaker including interrupter means and a stationary contact for the relay carried by the bridge of the arch, and adapted to connect the motor with the current source when engaged by the relay armature.
